US0D1011163S

(12) **United States Design Patent** (10) **Patent No.:** **US D1,011,163 S**
(45) **Date of Patent:** **** Jan. 16, 2024**

(54) **WOOD SPLITTING TOOL**

(71) Applicant: **Shibo Xiao**, Jingzhou (CN)

(72) Inventor: **Shibo Xiao**, Jingzhou (CN)

(**) Term: **15 Years**

(21) Appl. No.: **29/814,711**

(22) Filed: **Nov. 8, 2021**

(30) **Foreign Application Priority Data**

Nov. 2, 2021 (EM) 008742977-0002

(51) **LOC (14) Cl.** **15-09**

(52) **U.S. Cl.**

USPC **D15/127**

(58) **Field of Classification Search**

USPC D15/127; D8/7

CPC B27L 7/00; B27L 7/005; B27L 7/06; B27L
7/08

(57) **CLAIM**

The ornamental design for a wood splitting tool, as shown and described.

DESCRIPTION

FIG. 1 is a perspective view of a wood smiting tool, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the wood splitting tool and form no part of the claimed design.

1 Claim, 8 Drawing Sheets
